(57) **CLAIM**

The ornamental design for an electronic device with animated light display, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top view of a portion of an electronic device with animated light display showing a first image of the claimed design;

FIG. 2 is a second image thereof;

FIG. 3 is a third image thereof;

FIG. 4 is a front view of the electronic device of FIGS. 1-3;

FIG. 5 is a rear view thereof;

FIG. 6 is a left side view thereof, the right side being a mirror image thereof; and,

FIG. 7 is a bottom view thereof.

The broken lines in the figures show portions of an electronic device with animated light display that form no part of the claimed design.

The appearance of the animated image sequentially transitions between the images shown in FIGS. 1-3. The process or period in which one image transitions to another forms no part of the claimed design.
